ARTIFICIAL CALF

Filed March 30, 1929

UNITED STATES PATENT OFFICE

JOHN G. BALDEA, OF SALT LAKE CITY, UTAH

ARTIFICIAL CALF

Application filed March 30, 1929. Serial No. 351,433.

The present invention relates to improvements in artificial calf, and has for an object to provide an improved artificial calf adapted to be worn under the hose to impart a 5 flesher appearance and a better shape to the leg.

Another object of the invention is to provide an improved artificial calf which is adapted for washing, and will not be destroyed by perspiration, but which will retain its shape for a long period of time and which will fit to the leg without its presence being noticeable.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side view of an improved artificial calf constructed according to the present invention and shown as embracing the leg 25 indicated in dotted lines.

Figure 2 is a longitudinal section taken on the line 2—2 in Figure 4 through the device.

Figure 3 is an interior plan view.

Figure 4 is a top edge view, and

Figure 5 is a transverse section taken on the line 5—5 in Figure 3.

Referring more particularly to the drawings the device consists of a calf portion or section and a front portion or section. The 35 calf portion is preferably composed of a piece of soft and flexible leather 5, and a quantity of sponge rubber 6. In place of the sponge rubber hair, cotton, wool or other appropriate material may be substituted and I use the 40 term sponge rubber to include all such soft pliable materials. The sponge rubber 6 is placed on the inside of the leather, that is next adjacent the leg and both the leather and sponge rubber are covered by thin flexible 45 sheets of rubber 7 and 8 to protect the leather and sponge rubber from water and from the perspiration of the leg. The front leg section is composed of a thin sheet of flexible rubber 9. The sheet 9 may be a continuation of the 50 rubber sheet 7 and the rubber sheet 8 may be

made in the same piece with the sheets 7 and 9, being doubled or returned upon itself as indicated at 13 so as to provide an uninterrupted joint.

The front edge of the sheet 8 is preferably overlapped, as indicated at 14 upon the inner surface of the sheet 9 and is held thereto as by water proof cement, or other material.

The leather 5 preferably extends beyond the edge of the sponge rubber 6 to form a reinforcement for the fastening. The upper edges of the sheets 7 and 9 are turned over as indicated at 16 and 17 in Figure 3 and secured to adjacent inner portions by rubber cement or other appropriate material and the lower edges may be similarly overturned or the lower edges of the rubber sheets may be joined in any other appropriate way.

The device may be clamped together about the leg by any appropriate fastenings, preferably by means of the fastening shown in the drawings, which is known as the zipper fastening. This fastening is carried by wicks or tapes 18 having the complementary fastening members 19 and 20, and the slideable operating member 21 by which the members 19 and 20 are opened and closed by sliding movement of the operating member 21.

In the use of the device the calf is applied as shown in Figure 1, the zipper fastener or the other form of fastener lying at the side of the leg so as not to be observable and the lower and upper portions of the device are tapered to merge into adjoining portions of the leg. The leather 5 and sponge rubber 6 will be built up to the shape of the calf and will add to the bulk of the calf, imparting a 80 fleshier and a better shape.

The device may be washed when desired, the rubber sheets protecting the encased leather which adds the requisite stiffness to the device retaining its shape for a long time.

It is further to be noted that the padded portion of the device extends only at the back and sides of the leg and that the extremely thin rubber sheet 9 is stretched across the front of the leg and about the shin bone so that the device is held securely in place and adds no substantial additional thickness where it is not required. The stretching of 95 100

the thin sheet 9 will also serve to hold the device in place more securely than if the device was thickened all around.

It is obvious that various changes and modifications may be made in the details of construction and design of the above specifically described embodiment of this invention without departing from the spirit thereof, such changes and modifications being restricted only by the scope of the following claims.

What is claimed is:—

1. An artificial calf comprising a calf section composed of leather and sponge rubber, and thin sheets of rubber enclosing the leather and sponge rubber, a front section of thin sheet rubber for stretching over the front of the leg and jointed at one edge to the calf section, and fastening means at the side of the leg between the free edges of the calf and front sections.
2. An artificial calf comprising connected calf and front sections opening at the side of the leg, a stiffening layer in the calf section, a layer of soft material in the calf section between the leg and stiffening layer, said sections having reinforced edges at the opening and fastening means on the reinforced edges.
3. An artificial calf comprising a calf section of superposed thin rubber sheets, a front section of a thin rubber sheet in one piece with one of the calf section sheets and having the free edge of the other calf section sheet overlapped and secured thereon, the upper edges of the outer sheets being overturned on the inner sheets and secured thereto, stiffening and cushioning means in the calf, and fastening means for the sections.

JOHN G. BALDEA.
